DESIGN FOR A DRESS

Jack Siegel, New York, N. Y.

Application October 12, 1940, Serial No. 95,820

Term of patent 3½ years

To all whom it may concern:

Be it known that I, Jack Siegel, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof on a reduced scale.

The characteristic feature of my design resides in the combination on the dress disclosed of the specific braid trimmed front yoke member, with gathered fullness extending to the specific waist-yoke and the bow trimmed front opening, in association with the braid trimmed back, all as shown.

I claim:

The ornamental design for a dress, substantially as shown and described.

JACK SIEGEL.
